UNITED STATES PATENT OFFICE.

BEVILL WALLER WHITWORTH, OF CEDAR FALLS, IOWA, ASSIGNOR OF ONE-THIRD TO THOMAS A. WHITWORTH AND ONE-THIRD TO CHARLES S. WHITWORTH, OF CEDAR FALLS, IOWA.

FREIGHT-CAR GRAIN-DOOR.

1,272,325.

Specification of Letters Patent.

Patented July 9, 1918.

Application filed September 22, 1917. Serial No. 192,682.

To all whom it may concern:

Be it known that I, BEVILL WALLER WHITWORTH, a citizen of the United States of America, and a resident of Cedar Falls, 5 Blackhawk county, Iowa, have invented certain new and useful Improvements in Freight-Car Grain-Doors, of which the following is a specification.

My invention relates to improvements in door-closures, and the objects of my improvements are, first, to provide a removable sectional closure for the door-casing of a freight-car or other container or housing, having a movable section permitting a restricted opening of the closure; second, furnishing the closure with other movably connected parts to provide another opening at another location; third, to mount the closure to allow it to be bodily shifted relative to the door-casing and secured in that position, and otherwise to improve and modify the construction and mounting of a door as will be more specifically described in the specification, pointed out in the claims, and shown 15 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 20 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 25 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 30 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 35 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 40 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 45 in the drawings annexed hereto, wherein Figure 1 is a front elevation of my improved door-closure as mounted within a door-casing; Fig. 2 is a like view thereof with the lowest section thereof swung open to allow it to be bodily shifted relative to the door-casing and secured in that position, and otherwise to improve and modify the construction and mounting of a door as will be more specifically described in the specification, pointed out in the claims, and shown 50 in the drawings annexed hereto.

Similar numerals of reference denote cor-

responding parts throughout the several views.

My special object in this invention is to provide an improved construction of grain-door for freight or box-cars, but it is to be understood that my invention may be applied and used with or without any modification of its parts, as a door-closure for any other description of container or housing.

My improved closure is formed of a plurality of hingedly connected sections and suitably positioned to close the opening of a door-casing 3. The door is composed of a middle section 1 to which is hingedly connected a single swinging bottom section 2 by means of double-joint hinges, and to whose upper part is hingedly connected a plurality of swingingly connected sections 4 adapted to close the upper part of the door 65 opening. The double joint swinging connection or connections of the lowest section or flap 2 may be of any desired type, which will permit said section or flap to be given an upward translatory movement initially 70 before swinging it upwardly to disengage it from securing engaging-means. Preferably a pair of such double-joint connections are used positioned respectively near the ends of the sections, and comprise the following-described elements:

The numeral 10 denotes T-bars secured vertically across the end parts of said middle section 1, and whose webs have orifices to receive pintles 11 on which are pivotally 85 mounted the upper ends of the outwardly curved parts 13 of hinge elements, each of which has a channeled arm 14. Immediately underneath each arm-part 14 a vertical T-bar 21 is secured to the swinging section 2, 90 the upper end of the web thereof having an orifice to receive a pintle 12 to which the lower end of the curved part 13 is pivoted. This forms a double-joint connection between said sections, and, as shown in said 95 Fig. 8, the arm 14 may be manually lifted to both elevate and swing the section 2 relative to said middle section 1.

As best shown in said Fig. 10, the middle section 1 is provided with depending spaced 100 projections 32 between which said section 2 is mounted on said double-jointed hinges so

as to be flush therewith, and the meeting longitudinal edges of these sections are beveled at 29 to form a closer joint therebetween. Metal bars 7 are fixed vertically on 5 the rear end-parts of the middle section 1 and its prolongations, and said bars extend inwardly fixedly to overlap the abutting end-parts of the rear face of the swinging section 2, the lower ends of said bars having 10 forwardly projecting hooked parts 16 adapted to receive removably the lower edge of the section 2. When the section 2 is closed, with its lower edge secured in the hook 16, a turn-button 19 pivoted at 18 on the section 1 may 15 be turned over its upper edge to secure it at that location, and other turn-buttons 15 may be turned to engage the arm parts 14 of said hinge connection to hold the latter locked over the T-bars 21. The end edges of the 20 middle section 1 overlie the rear face of the casing jambs 3 and are secured to said jambs, by means of turn-buttons 8 which are pivoted on said jambs. As shown in Fig. 11, each turn-button 8 as also the other turn- 25 buttons mentioned, have projections 30 which overlie the elements which they fasten and also have offset oblique cam-edges 31. These cam-edges 31 engage the vertical edges of the sections or other parts which 30 they fasten when swung downwardly, forming a tight, compressive securing means, the cam in each case preventing the abutment from becoming displaced downwardly out of engagement with the object fastened. 35 This prevents separation of the door-parts under the jars of movement of the car.

The section 1 is reinforced on its front face by medial angles or T-bars 17, and the section 2 by medial T-bar 20. A horizontal bar 9 is secured to the rear face of the section 1 between the end-bars 7, to partially depend therefrom to overlap the section 2 and thus cover and protect the joint between said sections. The upper longitudinal edge 45 of the section 1 is covered by a metal strip to prevent wear. This upper edge also has hinged thereto to swing rearwardly a plurality of hinged sections 4, by means of hinges 5. These sections are narrower than 50 the section 1 and are, when swung upwardly into closed position against the jambs 3, secured thereto by means of hooks and staples 6.

The numeral 22 denotes a pair of guide- 55 plates having flanges secured to the rear faces of the upper parts of said jambs opposite the ends of said sections 4, said plates having slanting guideway slots 26 to receive therethrough the round shanks of headed or 60 headless pins or projections 23 on the end edges of the section 1. At the lower ends of said slots are recessed squared seats 27 (see Fig. 5) to receive said shanks to interlock therewith to hold the same from moving up-

wardly, as shown in said Fig. 9. At the 65 upper end of each slot 26 is a forwardly recessed seat or bearing 28 of rounded form, adapted to receive the shank of the pin 23 to permit rotation of the door in being swung upwardly to an entirely opened position, as 70 shown in said Fig. 5, wherein a pair of such doors are shown swung upwardly, and their lower ends detachably held in resilient hooked depending clips 25, supported on 75 rafters 24 of the car. This leaves the door opening in each case free and unobstructed. The slot 26 in each guide 22 is made slanting in order to provide clearance for projecting parts of the door when the latter is swung to its opened position. 80

The grain door shown, as mounted in a freight-car in Fig. 5, when closed, tightly seals up the door opening, and it, with its door casing, is positioned within the car relative to the ordinary car door and its casing not shown. The swinging drop sections 4 are each relatively narrow and hinged together so that one or more of them may be dropped inside the car to provide an opening of a desired type between the upper longitudinal edge of the middle section 1 and the top of the door casing, as may be required when different kinds of grain are being transported in the car. The opening thus provided is also utilized as an entrance 90 for receiving the grain in the loading of the car. The lowermost section 2 may be opened to permit evacuation of the grain from the car through the opening thus provided, by the use of the swinging arms 14. 100 When these arms are lifted, as shown in Fig. 8, the double-joint connection first lifts the section 2 upwardly out of engagement with the hook 16, and then swings the section outwardly. 105

Having described my invention, what I claim as new, and desire to secure by Letters Patent, is:

1. A door-casing, a sectional closure therefor whose sections are connected by double-joint hinges, the lowermost section having vertical longitudinally rigged bars fixed thereon, each hinge including an element projecting therefrom adapted to fit and engage with the rib on the adjacent vertical bar when the section and said element are respectively moved to a certain relative position, and clips on said lowermost section movable to detachably clamp said elements upon said ribs. 110

2. A door-casing, a sectional closure therefor whose sections are connected together by hinges which permit both translatory and swinging movements of one section relative to the one to which it is hinged, the uppermost of said sections having fixed thereon depending parts abutting on the ends of the swinging section, and having in the rear de- 115 120 125

pending bars extending across the lowermost section to project laterally therefrom at each end thereof to cover the joint between said section and said depending parts of the uppermost section, and said bars each having an upturned lower extremity adapted to receive and coengage with the lower edge of said last-mentioned section when in a pos-

tion closed against said bars and first-mentioned section.

Signed at Waterloo, Iowa, this 17th day ¹⁰ of Sept, 1917.

BEVILL WALLER WHITWORTH.
